US00D800515S

(12) **United States Design Patent** (10) **Patent No.:** **US D800,515 S**
Gonterman et al. (45) **Date of Patent:** **** Oct. 24, 2017**

(54) **PERSONAL FOOD DELIVERY APPARATUS**

(71) Applicant: **NumNum, LLC**, Suwanee, GA (US)

(72) Inventors: **Doug Gonterman**, Suwanee, GA (US);
Jessica Lineberry, Suwanee, GA (US)

(73) Assignee: **Numnum, LLC**, Duluth, GA (US)

(**) Term: **15 Years**

(21) Appl. No.: **29/557,946**

(22) Filed: **Mar. 14, 2016**

Related U.S. Application Data

(63) Continuation of application No. 13/694,237, filed on Nov. 9, 2012.

(57) **CLAIM**

The ornamental design for a personal food delivery apparatus, as shown and described.

DESCRIPTION

FIG. 1 is a top plan view of a personal food delivery apparatus showing our new design;

FIG. 2 is a right side view thereof. The left side view is a mirror image of the right side;

FIG. 3 is a top plan view of a second embodiment of a personal food delivery apparatus showing our new design, the right and left side views being the same as FIG. 2;

FIG. 4 is a top plan view of a third embodiment of a personal food delivery apparatus showing our new design, the right and left side views being the same as FIG. 2;

FIG. 5 is a top plan view of a fourth embodiment of a personal food delivery apparatus showing our new design, the right and left side views being the same as FIG. 2; and,

FIG. 6 is a top plan view of a fifth embodiment of a personal food delivery apparatus showing our new design, the right and left side views being the same as FIG. 2.
